UNITED STATES PATENT OFFICE

DAVID E. GRAY, OF CORNING, NEW YORK, ASSIGNOR TO CORNING GLASS WORKS, OF CORNING, NEW YORK, A CORPORATION OF NEW YORK

GRADING MACHINE

Application filed April 11, 1927. Serial No. 182,896.

My invention relates to automatic sorting or grading machines which sort or grade articles according to their respective weights.

While my invention is possible of application or ready adaptation to the weighing and sorting of various kinds of articles, I have found it particularly advantageous for weighing and sorting glass tubes. In addition to the general desirability of determining the weight of these tubes and sorting them accordingly, such a procedure assumes even greater importance as regards these particular articles by virtue of the fact that in many of the applications and uses of the same some knowledge of the wall thickness is very desirable. By previously determining the diameters of tubes of uniform length, by means of a gauging machine or otherwise, and supplying tubes of the same diameter to the grading machine, the latter will segregate these tubes into groups of substantially the same wall thickness.

The object of my invention is to provide a simple and efficient machine of the class described which will accurately, and with a minimum of attention, sort the articles by weight into such lots as are desired.

The manner in which I accomplish this is fully described in the following specification, and while, in its broader aspect, my invention is capable of embodiment in various forms, a preferred and desirable embodiment thereof is illustrated in the accompanying drawings, in which:

Fig. 1 is a side elevation, partly in section, of my improved machine;

Fig. 2 is an enlarged sectional view of the upper part of my machine, taken along the line 2—2 of Fig. 3, with the operating parts in a different position than in Fig. 1;

Fig. 3 is a front elevation, on a further enlarged scale, of the construction shown in Fig. 2, some of the structure being omitted;

Fig. 4 is a detail of a fulcrum shaft support;

Fig. 5 is a plan view of the machine with the parts in the position shown in Fig. 2, some of the structure being omitted;

Fig. 6 is a detail of one of the grading mechanisms, and

Fig. 7 is a similar view of the same mechanism with the parts in a different position.

Referring to the drawings, reference numerals 11 and 12 designate a pair of similarly constructed side standards affixed in any suitable manner to a base block 13. The latter is preferably mounted upon rollers 14, and may be provided, at its corners, with vertically adjustable legs 15, adapted to support the machine in immovable position, independently of the rollers.

Mounted in suitable bearings in the standards 11, 12, in vertically staggered relation to each other, as shown in Fig. 1, are horizontal mounting shafts 16, 17, 18, 19, 20, provided with identical interlocking gears 21, 22, 23, 24, 25, respectively, at one side of the machine, for simultaneous rotation of said shafts. These gears are actuated by a sprocket wheel 26, keyed to the lowest shaft 20, and connected by means of a sprocket chain 27 to a suitable electric motor (not shown).

Two additional horizontal shafts 30, 31 are mounted for rotation in bearings provided in projecting ears 28 (Fig. 1) on the upper parts of the standards 11, 12, and above these shafts a cross-beam 29 is also secured to the ears 28.

Fixedly mounted in standards 11, 12 is a series of cross-beams, as indicated at 32, each of which is horizontally aligned with one of the shafts 16, 17, 18, 19, 20, as shown in Fig. 1.

On each of the standards 11, 12 a series of corresponding ears 33 is provided, each pair of oppositely disposed ears serving as a mounting for one of a series of cross-beams 34.

A downwardly inclined magazine 35 (Figs. 1 and 5), for holding the tubes to be fed into the machine, is provided with similar side walls 36 that are secured to the cross-beam 29 in any well-known manner. The bottom of the magazine consists of a pair of spaced flat plates 38 (Fig. 5) which are secured to the cross-beam 29 by means of screws or bolts 39, which extend upwardly through the cross-beam and into the under sides of the plates. The plates 38 terminate

in ends 40 which are in proximity to the pan-arms of scales to be described hereinafter.

For receiving the tubes which have been weighed and sorted, there is provided a series of outwardly and downwardly inclined, similar compartments 41, hereinafter called grade-compartments. The bottom of each of these compartments is formed by a pair of spaced flat plates 42, which are secured to the cross-beams 34 by upwardly directed screws or bolts 43. The inner ends of these plates terminate in tapered edges 44, which normally contact with the extremities of the adjoining scales in the machine proper, and the outer ends of these plates (not shown) are provided with any suitable detents for retaining the tubes in the grade-compartments.

A series of similar guideways 45, arranged in alternately opposite directions, are provided between the successive stages of the machine. Each of these guideways 45 comprises a pair of spaced, correspondingly located, and downwardly curved bars 46 which are secured to the cross-beams 34 by bolts or screws 47.

Supported by each cross-beam 32, is a pair of spaced angle-irons 48, on which are mounted a pair of suspension plates 49 in which rest the knife edges 52 of a fulcrum shaft 50. The latter is generally of circular cross-section, except for two integral, spaced, wedge-shaped portions 51 which form the knife edges 52, these sections being equidistant from the ends 57 of the shaft. The ends 57 are pointed and contact very lightly with abutments 53 (Figs. 3 and 5) to prevent longitudinal displacement of the shaft.

The knife edges 52 of the wedge-shaped portions 51 rest in V-shaped notches in the plates 49, as shown in Fig. 4, the sides of these notches diverging at a sufficient angle to permit the desired rocking of the shaft 50 therein.

At spaced points along each fulcrum shaft 50, between the wedge-shaped sections 51, are mounted a pair of similar beam scales 56 (Figs. 3 and 5), the direction of which pair of scales is alternately reversed in each succeeding stage of the machine as shown in Fig. 1. The weight setting of the scales may be accomplished by integral weight incorporation, the provision of a longitudinally adjustable collar of determined weight, or any other well-known means, and in the particular embodiment herein described I have found it preferable to permanently incorporate the desired weights in the weight ends 58 of a number of scales, relying on substitution of an entire beam to provide the weight setting desired. The tube receiving end 59 of each scale 56, referred to as the pan-end, slopes downwardly, and terminates in a notch 60 (Figs. 5 and 6), the side walls of which incline downwardly and outwardly from the center, to provide a thin blade-like edge 62,

upon which the tubes are supported during the weighing operation.

I have found it preferable to so space the scales 56 from each other on the fulcrum shaft 50 that when a tube is weighed thereon the distance between each end of the tube and its respective supporting scale will be substantially equal to one quarter of the total length of the tubing. This locates the center of gravity of the tube at a point substantially midway between the pair of supporting scales, and results in more accurate weighing. Since the tubes in any one group are generally of uniform length, constant readjustment is unnecessary.

The scales in the various stages of the machine are adjusted for different weights, each successively lower scale requiring a heavier weight to overbalance it. This will result in a sorting out of the tubes in their downward passage in the order of increasing weight, such tubes as are of sufficient weight to overbalance all the scales being delivered to the bottom grade-compartment (Fig. 1).

For cooperation with each of the scales there is provided a discharging or ejecting mechanism, the two combined constituting the individual grading mechanisms. These are duplicated in each stage of the machine except the last, but are arranged to operate in alternately reversed directions in the successive stages (Fig. 1).

As shown in Figs. 3 and 5, a pair of right and left hand dischargers 63 are keyed to shaft 16 and each discharger consists of a pair of duplicate blades 67, 68, a thin lug 65 being provided on each blade for cooperation with the scales as described hereinafter. The dischargers are mounted in close proximity to the pan-ends 59 of the scales so that, when rotated, they will strike against the projecting ends of the tube after it has been weighed and eject it into either the grade-compartment or the guideway. Also keyed to shaft 16, and on the side of each discharger nearest the center of the machine is a stabilizer 64 to support the scale beam during the loading operation. The stabilizers 64 and the lugs 65 may be made integral with the dischargers or may be attached thereto in any well-known manner in which event the stabilizers constitute a hub-like reinforcement for their respective dischargers.

The specific construction, arrangement, and operation of dischargers and scales is best shown in Figs. 6 and 7, which show a discharger 63 with one of its blades 68 in operating relationship with the scale 56. On the side of the pan-end 59 of the scale beam 56 which adjoins the inner face of the discharger 63 there is provided a substantially triangular-shaped projection 69 whose bottom face 70 is slightly curved and forms a substantial continuation of the bottom of the pan-end 59. The upper surface 71 of this projection is

shown as substantially straight but could be slightly curved if desired. The lugs 65 on the discharger project laterally therefrom to a sufficient extent to contact with the projection 69, but not sufficiently to touch the wall of the scale beam proper (Fig. 3).

To eliminate misleading and incorrect indications of the weight of a tube, resulting from loading momentum and motion of the tube on the scales, stabilizer 64 holds the scale against depression until the tube has come to rest thereon. The stabilizer 64 is positioned in radially spaced relation to the discharger blades 67, 68, and its outer ends terminate in cam faces 72 whose curvature corresponds to that of the bottom of scale 56, so that one of the cam faces 72 will contact with the bottom of the scale beam 56 when a tube rolls out onto the pan-end 59, and sufficiently thereafter to assure the tube's having come to rest. The relative lengths of these contacting surfaces will be such that there will be continuous supporting contact during the maximum period of activity on the scales prior to the tube's coming to rest. When the stabilizer is rotated out of contact with the scale, the latter is liberated for weighing and the subsequent action of the selective discharging means.

The action and relation of parts at the pan-end of the scales, just described for the first stage of the machine, is exactly the same in the succeeding stages, with the exception of the last or bottom stage, which differs from the preceding stages in the omission of the weighing mechanism (see Fig. 1).

Although I have previously described both of the ejectors 63 in each stage as being provided with a pair of lugs 65, it will be apparent that these lugs may be omitted from one of such ejectors in each stage. Since both scales are secured to a common fulcrum shaft 50, and both dischargers are secured to a common shaft 16, the action of one of the sets of discharger and scale mechanisms will be correspondingly reproduced in the other set in the same stage of the machine, and accurate adjustment to assure corresponding action of the lugs on each ejector with its respective scale is thereby avoided.

Upon one side of the upper central portions 75 (Fig. 1) of the standards 11 and 12 is mounted a cross-beam 76 (Figs. 3 and 5) provided with spaced, T-shaped channels 77 to form slideways for a pair of escapement blocks 78. The upper ends of these blocks are provided with threaded pins 79 which support adjustable collars 81 (Figs. 1 and 2), to limit downward movement of the escapement blocks by contact with the cross-beam 76. Mounted on the outer surface of the escapement blocks, and projecting therebelow, are stops 82 to limit the discharge of tubes from the magazine 35.

Mounting blocks 84 are secured to the

cross-beam 76 at points adjoining the escapement blocks, and extend horizontally from said beam out over the scale beams 56 to points slightly beyond the ends 40 of the plates 38 (Figs. 1 and 3). Adjustable detents 85, provided with elongated U-shaped recesses 86, are bolted on said mounting blocks 84 directly over the scale beams (Figs. 2 and 3). Additional adjustable detents 87 are mounted on each of the cross beams 32 over the other scale beams.

A pair of spaced brackets 88, provided with slideways 89 for a pair of reciprocating cut-off members 90, are mounted on the upper cross-beam 32 in alignment with the escapement blocks 78. Each member 90 has a projection 91 which is linked to one of a pair of spaced bell-crank levers 92 which are fixedly secured to the rock shaft 31 for actuation by a pair of cams 93 fixedly secured on cam shaft 30 (Figs. 2 and 5).

Each set of cam, bell-crank lever, and associated mechanisms is a duplicate of the other, hence, a description of one will suffice. As shown in Figs. 1 and 2, the rotation of cam shaft 30 actuates the bell-crank lever 92, and hence the feed regulating members 90, 78, 82, through the contact of cam 93 with a roller 94 on one arm of the bell-crank lever, a coil spring 95 holding the roller against the cam. Fig. 1 shows the cam in the position which carries the member 90 to the top of its stroke and with it members 78 and 82, Fig. 2 shows it in the opposite position, with those members at the bottom of their stroke.

A gear 96, mounted on the end of cam shaft 30 (Fig. 5), is motivated by means of an idler 97 on a stub shaft 98, which idler also meshes with gear 22 on shaft 17. Since the discharger 63 is double bladed, and is therefore adapted to discharge two tubes during each revolution, the cam 93 should make two revolutions for each revolution of the discharger in order to supply two tubes, and the gears are accordingly given a two to one ratio.

The operation of the machine is as follows, it being understood that the operations described are performed in duplicate at both ends of the tubes as will be evident from an inspection of Figs. 3 and 5, and also that, if desired, only one of the dischargers need be provided with the lugs 65, as hereinbefore noted.

With the parts in the position shown in Fig. 1, and a number of tubes supplied to the magazine 35, the tubes will roll down the incline until the foremost one reaches the cut-off member 90, as indicated at T¹, Fig. 1 (shown in dotted lines Fig. 3).

Rotation of cam 93 to the position shown in Fig. 2 retracts the cut-off 90, by the action of spring 95 on bell-crank 92, allowing the foremost tube to reach stop 82 and occupy position T².

Further rotation of cam 93, to the position shown in Fig. 1, will elevate cut-off 90, thus interposing it between the foremost tube and those behind it, raising escapement block 78 5 and releasing this tube to position T^s , in which it is held by the top edge of rotating discharger blade 67 and detent 85.

As the discharger blade 67 is rotating to the position shown in Fig. 2, stabilizer 64 10 will rotate into the position in which it supports scale 56, and when the parts have reached the position of Fig. 2 the tube will have advanced onto the scale 56 and will be coming to rest in notch 60, position T^s . At 15 this time the discharge of other tubes from the magazine will be prevented by the lowering of stop 82.

In the further operation of the machine the stabilizer 64 will rotate clear of the scale, 20 and weighing of the tube will take place prior to the advancement of the other discharger blade 68 into the operative position shown in Figs. 6 and 7.

If the tube on the scale is of insufficient 25 weight to depress it, the lug 65 (Fig. 6) will pass underneath the projection 69 along the face 70, and hold the end of the scale up against the projecting end 44 of the grade-compartment 41 while the discharger blade 30 68 wipes the tube into this grade-compartment, position T^s .

If the tube overbalances and therefore depresses the scale, the lug 65 (Fig. 7) will pass above the projection 69, either positively 35 holding the scale down, or simply preventing resumption of the undepressed position, while the discharger blade 68 pushes the tube off the scale (position T^s) onto the guideway 45.

It will be noted that the forward end of 40 lug 65 tapers to a fine edge, as does also the rear end of projection 69, and these features, as well as the particular fulcrum shaft support, provide a delicate selection that will 45 result in extreme accuracy in grading to the extent that even the exceedingly slight depression of the scale initiated by a very slightly overweight tube will be translated into a depression of sufficient magnitude to 50 permit discharge of the tube onto the guideway 45, as in Fig. 7.

After being discharged onto the guideway 45 the tube will follow the moving discharger blade 68 in the position T^s Fig. 2. Upon 55 further rotation of the blade the tube will roll down the lower end of guideway 45 to position T^s , Fig. 1, where further advancement is restrained by detent 87 and the top of the discharger blade in the second stage 60 of the machine, in the same manner as described in relation to position T^s .

These operations are repeated until each tube has reached its proper grade-compartment.

65 From the above description it will be ap-

parent that my grading machine possesses many inherent advantages which result in increased operative efficiency. The vertically staggered relationship of the grading mechanisms and guideways produces a compact 70 structure which requires but a minimum of floor space and is readily accessible for inspection and maintenance. The rotary action throughout the machine also conserves space, is peculiarly advantageous in combination with the vertically staggered arrangement due to the horizontal and vertical action in the selective discharging operation, and produces less jarring action than discharging or conveying mechanisms having straight line motion. The arrangement and structure of the specific grading mechanism provides an extremely delicate grading selection without sacrificing the ruggedness essential for successful commercial operation. 80

While I have herein disclosed a preferred embodiment of my invention, I do not desire to be limited to the specific details of arrangement and construction described, except as indicated by the following claims.

I claim:

1. In an assorting machine, the combination of a plurality of vertically-spaced scales set for progressively increasing weights, guideways between said scales, a plurality of grade-compartments, and means for delivering each article weighed to one of the grade-compartments.

2. In an assorting machine, the combination of a plurality of spaced scales arranged in the same vertical plane and set for different weights, connecting guideways between said scales, grade-compartments associated with said scales, and means to positively direct each article to a compartment or to a guideway.

3. In an assorting machine, the combination of a beam scale set for a predetermined weight, a guideway leading away from said scale, a receiving compartment normally forming a continuation of the pan-end of said scale, means for discharging weighed articles from said scale, and means operating in conjunction with said discharging means for positively holding said pan-end in feeding relation to said receiving compartment or in feeding relation to said guideway.

4. In an assorting machine, the combination of a plurality of scales set for different weights, grade-compartments cooperating with said scales for receiving articles of equal or less weight than the weight-setting of their respective scales, guideways for conducting to successive scales articles of greater weight than the weight-setting of their respective scales, and means operable in conjunction with the pan-ends of said scales for delivering articles weighed thereon to the respective compartments or guideways.

5. In an assorting machine, the combina-

tion of a scale set for a certain weight, a compartment for receiving from said scale articles whose weights are equal to or lighter than said weight, a guideway for receiving articles heavier than said weight, and a rotary discharger for said scale.

6. In an assorting machine, the combination of a plurality of scales arranged in vertical relation and set for different weights, 10 a guideway leading from each scale for receiving articles which overbalance said scale and delivering them to a lower part of the machine, a grade-compartment leading from each scale for receiving articles which do not 15 overbalance said scale, and means operating in conjunction with said scales for directing said articles to said guideways or to said compartments.

7. In an assorting machine, the combination of a plurality of scales set for predetermined weights, a guideway leading from each scale for receiving articles which overbalance said scale and delivering them to a lower part of the machine, a grade-compartment leading from each scale for receiving articles which do not overbalance said scale, means for discharging weighed articles from said scales, and means mounted directly on the scales and cooperating with the discharging means during the discharging operation for facilitating the discharging action to said guideway or to said compartment.

8. In an assorting machine, the combination of a beam scale, means for discharging weighed articles therefrom, means for stabilizing said scale prior to each weighing operation, and means on the discharging means for engaging the pan-end of said scale for maintaining the scale in the relative position initiated by the weight of an article.

9. In an assorting machine, the combination of a scale beam mounted on a stationary pivot, means for discharging weighed articles therefrom, means connected with said discharging means and operating in advance thereof for stabilizing said scale prior to each weighing operation, and means mounted on the discharging means and cooperating with said scale for maintaining the scale in the relative position initiated by the weight of an article.

10. In an assorting machine, the combination of a movable scale beam, a plurality of spaced surfaces on said scale beam, article discharging means mounted for movement in a plane parallel to the plane of movement of the scale beam, and means carried by the discharging means for cooperation with one or the other of said surfaces during the discharging operation according to the relative position initiated by the weight of an article thereon.

11. In an assorting machine, the combination of a scale, means for stabilizing said scale during the loading of articles thereon,

means for discharging the weighed articles therefrom, and a common rotatable support on which said stabilizing means and said discharging means are mounted.

12. In an assorting machine, the combination of a scale including a movable beam, means for stabilizing said scale beam during the loading of articles thereon, means movable in a plane parallel with the plane of movement of the scale beam for discharging the weighed articles therefrom, and means mounted on the discharging means and cooperating with said scale to maintain said scale during the discharging operation in the relative position initiated by the weight of an article thereon.

13. In an assorting machine, the combination of a plurality of beam scales set for predetermined weights and arranged in staggered vertical relation, each scale being disposed in the opposite direction from the one directly above it, grade-compartments cooperating with said scales, and guideways connecting said scales, each guideway leading in the opposite direction from the one directly above it.

14. In an assorting machine, the combination of a plurality of beam scales set for predetermined weights and arranged in staggered vertical relation, the pan-end of each scale being disposed in the opposite direction from the one directly above it, grade-compartments cooperating with said pan-ends, guideways connecting said scales, each guideway leading in the opposite direction from the one directly above it, and rotatable discharging members cooperating with each scale for directing articles weighed thereon to said grade-compartments or to said guideways.

15. In an assorting machine, the combination of a fulcrum shaft, a plurality of scale beams mounted in spaced relation thereon for simultaneous operation, means movable in a plane parallel with the plane of movement of the scale beams for discharging weighed articles from said scale beams, and means associated with said discharging means and with one of said scale beams for maintaining said scales depressed or undepressed, according to the weight of the article thereon.

16. In an assorting machine, the combination of a fulcrum shaft, a plurality of scales mounted in spaced relation thereon for simultaneous operation, a grade-compartment associated with said scales, a guideway leading from said scales, and means cooperating with one of said scales to maintain said scales in cooperative relation with said receiving compartment or said guideway according to the weight of the article on said scales.

17. In an assorting machine, the combination of a scale set for a certain weight, a grade-compartment for receiving articles of the

same or less weight than that for which the scale is set, a guideway for receiving articles of greater weight, and means for maintaining the weighing end of said scale in continuity with said grade-compartment during the delivery thereto of articles of appropriate weight.

18. In an assorting machine, the combination of a scale, a loading platform adjoining said scale, and means for discharging weighed articles from said scale, said last mentioned means being so positioned with respect to the loading platform that it will prevent loading said scale during the discharging movement of the discharging means.

19. In an assorting machine, the combination with a scale, of means for loading articles thereon, and means for discharging articles therefrom, said last named means preventing the loading of the scale during its discharging movement.

20. An assorting machine which includes a plurality of scales set for progressively increasing weights, guideways between the scales to receive articles which tip the scales, a grade compartment associated with each scale, and means for delivering each article which fails to tip a scale into the corresponding grade compartment.

DAVID E. GRAY.
